UNITED STATES PATENT OFFICE

TULLY LA TESSA, OF CHICAGO, ILLINOIS, ASSIGNOR TO J. A. OLSON COMPANY, OF CHICAGO, ILLINOIS, A CORPORATION OF ILLINOIS

DESIGN FOR A MIRROR FRAME

Application filed June 6, 1929. Serial No. 31,576. Term of patent 7 years.

To all whom it may concern:

Be it known that I, TULLY LA TESSA, a citizen of the United States, residing in Chicago, county of Cook, and State of Illinois, have invented a new, original, and ornamental Design for a Mirror Frame, of which the following is a specification, reference being had to the accompanying drawing, forming part thereof.

In the drawing—

vation of the mirror frame, showing my new design, the design being shown in full lines on one-half of the mirror at the left with an outline only shown on the righthand half.

I claim:

The ornamental design for a mirror frame as shown and described.

TULLY LA TESSA.
